UNITED STATES PATENT OFFICE.

ROBERT BEYRLE, OF LOS ANGELES, CALIFORNIA.

GOLD SAVING AND AMALGAMATING MACHINE.

1,037,195.

Specification of Letters Patent.

Patented Sept. 3, 1912.

Application filed July 29, 1911. Serial No. 641,390.

To all whom it may concern:

Be it known that I, ROBERT BEYRLE, a citizen of the United States, residing at Los Angeles, in the county of Los Angeles and 5 State of California, have invented a new and useful Gold Saving and Amalgamating Machine, of which the following is a specification.

This invention relates to certain new and 10 useful improvements in amalgamating machines, and the objects thereof are to provide an improved and simplified structure of this character, which embodies novel means for effecting adjustment of the upper 15 rifle member, and to otherwise generally improve machines of this type.

In the drawings, Figure 1 is a view partly in side elevation and partly in section of the present invention; Fig. 2 is a fragmentary 20 top plan view; Fig. 3 is a fragmentary bottom plan view of the upper disk; Fig. 4 is a sectional view of one of the division ribs, and Fig. 5 is a perspective view of one of the 25 rifle cleats.

A circular receptacle A is provided with a central support A¹ in which a spindle H is journaled, the spindle having an annular shoulder H², which engages the upper end 30 of the support A¹, the lower end of the spindle being engaged by set screws H¹ which are projected through the support to impinge against the spindle to prevent upward movement of the latter.

Loosely mounted on the spindle H is the 35 hub E of a frame which has an annular flange E¹ at its lower end which latter has the upper amalgamating ring C secured thereto by screws C¹. Inclined rods D are 40 adjustably secured by nuts to lugs E² of the frame E and are also secured to the ring C adjacent the periphery of the latter. On the upper face of the ring C a plurality of ribs D² are secured, these ribs forming a 45 number of divisions thereon. On the under face of the ring C rifle cleats R are secured.

A cap plate J seats on the upper end of the hub E and is secured to the latter by bolts K. An eye bolt L is threaded through 50 an opening provided therefor in the cap plate and has its lower end bearing on a washer L¹ which latter seats on the top end of the spindle H, so that when the bolt is turned by the hand wheel M that is rigidly 55 secured thereon, it will effect raising or low-

ering of the cap plate and the frame connected thereto. A lock wheel N is used to engage on top of the cap plate J to hold the bolt L against accidental turning.

A pulley P engages over the cap plate 60 and the upper end of the hub E and is secured to each by set screws P¹ whereby power when applied to the pulley effects rotation of the frame and connected parts. The pulley is made of dish-shape so as to 65 act as a hopper for feeding material to the machine through the downwardly extending inclined pipe P² that is connected to the pulley.

The bottom amalgamating plate which is 70 ring-shaped is secured to the bottom of the receptacle A and is covered with suitable amalgamating material C³ the ends of which latter extend downwardly to engage sealing material W, preferably pitch. 75

The central support A¹ is surrounded by a sleeve A² arranged in spaced relation thereto and covered on its exterior by amalgamating material C⁴. By this construction any overflow from the tub will pass over 80 the open top end of the sleeve and escape downwardly through the interior thereof to a suitable drain, not shown.

In operation the crushed ore or other material is received in the receptacle A, the latter being nearly filled with mercury and water, the ore or other material passing 85 between the upper and lower amalgamating rings whereupon any gold or the like is collected on the parts C², C³, C⁴ and the rifle cleats R. 90

What is claimed is:

1. In an amalgamating machine in combination with a receptacle, an upper rifle member rotatably mounted in said receptacle and a pulley connected to said member for rotating same, said pulley being of dish-shape so as to receive material that is to be fed to the receptacle and a downwardly inclined pipe extending up through the pulley bottom and extending down into the receptacle to feed the material from the pulley to the upper rifle member at a point substantially central of the radius thereof. 95

2. In combination with a receptacle, a central sleeve projecting through the bottom of said receptacle, a support within the sleeve spaced therefrom, a spindle having its lower end rigidly secured to the support and having a central shoulder which seats 100

110

on the upper end of the support, a riffle member having a hub that is received over the upper end of said spindle, a cap plate removably bolted to the top end of the hub, 5 a screw threaded through said cap plate and having a hand wheel thereon, and a pulley secured to both the hub and the cap

plate, said screw being for engagement with the top end of the spindle.

ROBERT BEYRLE.
